US00D524251S

(12) **United States Design Patent** (10) Patent No.: **US D524,251 S**
Lim et al. (45) Date of Patent: ** Jul. 4, 2006

(54) **REMOTE CONTROL DEVICE FOR
ELECTRONIC EQUIPMENT**

(75) Inventors: **Wai-Loong Lim**, Menlo Park, CA (US); **Mieko Kusano**, Cambridge, MA (US); **Robert A. Lambourne**, Cambridge, MA (US); **Raymond L. Gradwohl**, Saratoga, CA (US); **Jacques Gagne**, Los Gatos, CA (US)

(73) Assignee: **Sonos, Inc.**, Santa Barbara, CA (US)

(**) Term: **14 Years**

(21) Appl. No.: **29/199,212**

(22) Filed: **Feb. 11, 2004**

(51) **LOC (8) Cl.** **13-03**

(52) **U.S. Cl.** **D13/164**

(58) **Field of Classification Search** D13/168; D10/104, 106; D14/218, 247; 340/825.22, 340/825.24, 825.25, 825.31, 825.36, 825.69, 340/825.71, 825.72; 341/20, 22, 173, 176; 348/734; 455/100, 151.1–151.4, 352–355; 463/39; 700/17, 18, 19, 22, 83

(57) **CLAIM**

We claim the ornamental design for a remote control device for electronic equipment, as shown and described.

DESCRIPTION

FIG. 1 is a top view of the remote control device constructed in accordance with the invention;

FIG. 2 is a front view of the remote control device constructed in accordance with the invention;

FIG. 3 is a right side view of the remote control device constructed in accordance with the invention (the left side view is mirror image thereof);

FIG. 4 is a bottom view of the remote control device constructed in accordance with the invention; and,

FIG. 5 is a rear view of the remote control device constructed in accordance with the invention.
